UNITED STATES PATENT OFFICE.

ALFRED GREENAWAY, OF LOUISVILLE, KENTUCKY.

DEVICE FOR HOLDING TILE-SETTINGS.

SPECIFICATION forming part of Letters Patent No. 400,076, dated March 26, 1889.

Application filed May 5, 1888. Serial No. 272,935. (No model.)

To all whom it may concern:

Be it known that I, ALFRED GREENAWAY, a citizen of the United States, residing at Louisville, in the county of Jefferson and State 5 of Kentucky, have invented certain new and useful Improvements in Devices for Holding Tile-Settings, of which the following is a specification.

This invention relates to tile-holders for fire- 10 places; and it has for its object to provide a device of this character whereby the tiles will be securely retained in place, and which will furthermore possess advantages in point of simplicity, inexpensiveness, durability, and 15 general efficiency.

In the drawings, Figure 1 is a perspective view of a section of a tile-holder embodying 20 my invention. Fig. 2 is a longitudinal sectional view. Fig. 3 is a transverse sectional view. Fig. 4 is a perspective view of a modification. Fig. 5 is a sectional view of said modification.

Corresponding parts in the figures are denoted by the same letters of reference. 25 Referring to the drawings, A designates a casing, which is preferably formed of sheet metal and secured around the edge of the fire-place in any suitable manner. The sides 30 a of the casing are bent at about right angles to the bottom a', and the edges of the sides are preferably bent inwardly and around a wire, a³, for strengthening said edges. The sides are braced by rods B, provided across 35 the casing, having nuts b' upon the screw-threaded ends b at each side of the sides a.

C designates a centrally-disposed longitudinal strip, preferably of sheet metal and cut away at its sides, as shown at c, said sides being bent to form right-angular projections c', 40 which project into the cement for holding the tiles and retain it within the casing.

In the modification illustrated in Figs. 4 and 5 I have provided a centrally-disposed raised

strip, D, bent to form angular portions d, which rest upon the bottom a' and are secured thereto. 45

E designates a series of transverse raised strips, which are secured at their centers to the strip D and at their ends to the sides a, whereby the latter are strengthened and braced.

The construction and advantages of my invention will be readily understood by those skilled in the art to which it appertains.

The cement is placed within the holder and secured therein by the central strip and cross-braces, and the tiles are secured upon the outer 55 surface of the cement and fit closely against the sides of the casing, thereby presenting a neat and attractive appearance.

I claim as my invention—

1. In a tile-holder for fire-places, the combination, with the casing comprising the back and the sides bent at an angle thereto, of a longitudinal strip secured along said back and provided with projecting portions, substantially as and for the purpose set forth. 60

2. In a tile-holder for fire-places, the combination, with the casing, of a longitudinal strip secured along the back of the casing, said strip comprising the central secured portion and the angular projections extending therefrom, 70 substantially as and for the purpose set forth.

3. In a tile-holder for fire-places, the combination, with the casing adapted to be disposed at the edge of the fire-place and comprising the back and the sides bent at an angle to the 75 latter, of a longitudinal strip having its main portion secured to said back and provided with angular projecting portions, and transverse retaining-braces secured to the sides, substantially as and for the purpose set forth. 80

In testimony whereof I affix my signature in presence of two witnesses.

ALFRED GREENAWAY.

Witnesses:

JAS. A. EDMONDS,
ALF. N. ROTH.
